LAST JACK

Charles J. Gross, Melrose, Mass., assignor to
 United Shoe Machinery Corporation, Borough
 of Flemington, N. J., a corporation of New
 Jersey

Application June 14, 1940, Serial No. 349,483

31 Claims.

(Cl. 12—123)

The present invention relates to a support for holding a lasted shoe in a convenient position for the application of sprayed material thereto, for example, latex or other cement, lacquer, etc., and particularly to such a support adapted to hold a lasted shoe so that it may be moved freely from one position to another during the spraying.

Heretofore it has been the usual procedure for an operator to hold a lasted shoe in one hand within a spray booth and to apply the desired material to the shoe with a spray gun held in the other hand. This handling of the shoe resulted, at times, in soiling the shoe which, in turn, tended to interfere with secure adhesion of the coating material. Moreover, some of the sprayed material was bound to be deposited on the operator's fingers and from there would pass to shoes subsequently handled. Altogether it was an untidy procedure.

It is an object of the present invention, therefore, to provide a support for a lasted shoe, so arranged that the shoe may be turned from one position to another without being touched by the hands of the operator and so constructed that the last may be mounted and dismounted with the minimum amount of effort on the part of the operator.

In order that the lasted shoe may be moved readily into substantially any desired position to facilitate the application of sprayed material, the support for holding the lasted shoe is provided with a last pin having means for retaining the last thereon regardless of the position to which the last is turned. The support and consequently the last pin are movable in an arc about a vertical axis, and the last pin is movable angularly about a horizontal axis and rotatable on its own axis. The aforementioned movements may take place in any order of sequence so that the supported last may be moved freely from one position to another.

In one of its preferred forms, as illustrated herein, the last pin is provided with locking means which will serve to retain a normal last. Occasionally, however, lasts are found in which the thimble hole is of an unusual size or is worn to such an extent that the relatively small range afforded by the locking means of the last pin referred to above is insufficient to provide proper gripping action. To provide for these unusual cases, another embodiment of the invention is shown herein in which the last pin comprises two members arranged to lie side by side with their inner faces in adjacent substantially par-

allel planes face to face, one of the members being adapted to be moved relatively to the other so that the last pin may be expanded or contracted. In this embodiment there is provided 5 means associated with one of the members whereby it is urged to turn to a position in which its face lies at an angle to the corresponding face of the other member thereby to expand the last pin to lock a last thereon, and means to 10 return the members to nonangular position thereby to contract the last pin to release the last.

In some classes of work it is desirable to be 15 able to mount the last on the last pin and remove the same therefrom without manipulation of the locking means, thereby relieving the operator to a great extent and permitting faster operation. To this end, the last jack, including its last pin, may be mounted on a support so 20 that it may be moved from a loading position to an operating position, the movement of the jack from the loading to the operating position automatically locking the last on the last pin, and the return of the jack from the operating 25 position to the loading position releasing the last. A feature of this construction resides in means for preventing movement of the last pin while it is in its loading position.

Several specific embodiments of the invention 30 will now be described with reference to the accompanying drawings, in which

Fig. 1 shows an elevation of the support and the last jack, the latter being in section;

Fig. 2 is a view of the locking portion of the 35 last pin with a last mounted thereon;

Fig. 3 is a section taken on the line III—III of Fig. 1;

Fig. 4 is an elevation of the last jack;

Fig. 5 is an elevation of the support and a 40 modified last jack, the latter being in section;

Figs. 6 and 7 are views of the free end of the last pin of Fig. 5 in closed and open position, respectively;

Fig. 8 is a section on the line VIII—VIII of 45 Fig. 5;

Fig. 9 is an elevation of a modified support and last jack, the latter being in section;

Fig. 10 is a section on line X—X of Fig. 9; and

Fig. 11 illustrates a counterbalance for the last jack shown in Fig. 9.

Referring to Fig. 1, the last jack P is mounted at one end of an arbor 10 the opposite end of the arbor being received in a sleeve 12 formed at the end of a yoke-shaped arm 14 whereby the

arbor is supported in a horizontal position. A collar 16 is fastened to the inner end of the arbor by a pin 18, the collar retaining the arbor in place. A washer 20 is disposed between the collar and the inner end of the sleeve 12, the washer being formed of some material which will afford frictional resistance to turning when the collar 16 is drawn up tight against the washer. Another washer 22 is placed on the arbor 10 against the outer end of the sleeve 12 and forms a bearing surface for one end of a coiled spring 24 surrounding the arbor, the opposite end of the spring abutting a collar 26 slidably mounted on the arbor. The collar 26 may be adjusted on the arbor to vary the compression of the spring 24, a set screw 28 locking the collar in the selected position. By adjusting the position of the collar 26, the friction between the collar 16, the washer 20 and the inner end of the sleeve 12 may be varied to control the turning of the arbor in the sleeve.

The inner ends of the yoke-shaped arm 14 are joined by a vertically disposed sleeve 30 (Fig. 9), the latter being pivoted to a bracket 32 by means of a pintle 34 whereby the yoke-shaped arm 14, the arbor 10 and the last jack P may be swung as a unit in a horizontal plane about the vertical axis of the pintle.

The free end of the arbor 10 is enlarged at 36 and is provided with a bore 38 adapted to receive the last jack P and to hold the same for movement angularly about the horizontal axis of the arbor and rotatably about its own axis. The last jack comprises a sleeve 40 reduced at one end at 58 (Figs. 1 and 9) to provide one part of a two-part last pin, the sleeve occupying the bore 38 and being retained therein by a C-shaped head 42 the lower arm 41 of which bears against one side of the enlargement, and by a collar 44 which bears against the other side of the enlargement, the collar being fixed to the sleeve by a set screw 46. The upper arm 48 of the C-shaped head is provided with an aperture 50 to receive the neck 52 of a handle 54, the handle being fixed to the arm 48 by a set screw 56, as illustrated. The provision of the handle 54 permits the operator to turn the last jack about its own axis, about the horizontal axis of the arbor, and to swing it in a horizontal plane about the vertical axis of the pintle without touching the lasted shoe which is mounted on the last pin (Fig. 2) and locked thereto, as will now appear.

The part 58 of the last pin is made slightly smaller in diameter than the inside diameter of a standard last thimble 60 (Fig. 2) so that the last L may readily be placed thereon without using force. The other part of the last pin shown at 62 is of substantially the same diameter as the part 58 and affords means for locking the last on the last pin. The part 62 is disposed below the part 58 in aligned end-to-end relation therewith so that in one position (Fig. 1) the part 62 forms a concentric extension of the part 58 of the last pin and in another position (Fig. 2) it is eccentric to the part 58. The eccentricity which may be obtained between the part 58 and the part 62 within the confined space afforded by the last pin thimble 60 is sufficient to bind the last L upon the last pin.

The part 62 is formed at one end of a spindle 64, the axis of which is substantially parallel to the axis of the part 58 and offset therefrom so that rotation of the spindle 64 turns the part 62 from a concentric to an eccentric position with respect to the part 58 and vice versa whereby the

last may be locked on the last pin or released and removed from the last pin at will. To this end, the sleeve 40 is provided with a bore 66 arranged longitudinally thereof, the bore extending through the part 58 of the last pin. The bore is eccentric to the axis of the part 58 and receives the spindle 64. A lever 68 whereby the spindle 64 may be turned in the bore is mounted near the opposite end of the spindle and is secured thereto by a pin 70 (Fig. 3). The lever 68 is provided with a hub 69 which surrounds the end of the spindle, the free end of the hub 69 being journaled in a recess 72 formed in the neck 52 of the handle 54. A coil spring 74 is placed about the hub 69 under torsional displacement, one end of the spring being anchored to the handle 54 and the other end to the lever 68, as illustrated in Fig. 1. The force exerted by the spring 74 turns the lever 68, and consequently the spindle 64, to a position in which the part 62 of the last pin is eccentric to the part 58 (Fig. 2). The lever 68 terminates in an extension 71 having a handle or thumb-piece 76 integral therewith which serves as a means for turning the lever in opposition to the spring so that the parts 58 and 62 are brought into concentric relation, thereby releasing the last. In order to prevent the part 62 from being moved beyond the point of maximum eccentricity, and also to limit the degree of eccentricity, an adjustable screw 73 is mounted on the extension 71, the end of the screw being arranged to abut the lower arm 41 of the head 42.

To prevent relative turning movement between the last and the last pin, a depending flange 79 is arranged to engage the neck of the last (Fig. 2). This flange is formed integral with a collar 75 which is mounted on the part 58 of the last pin against the collar 44 and is fixed to the last pin by means of a set screw 77.

The weight of the last and the lasted shoe fixed to the end of the last pin constitutes a turning moment which, if the arbor 10 were freely rotatable, would be sufficient to turn the arbor 10 in the sleeve 12, thereby causing the last to fall to the position shown in Fig. 2 whenever the operator releases his hold on the knob 54. This would be a nuisance and result in a waste of time since the operator would have to move the last back each time it fell out of position and, furthermore, it would necessitate the constant employment of one hand to hold the last in position. The washer 20, the spring 24, and the collar 26 are, therefore, provided to counteract the turning moment so that the last will remain in whatever position it is placed without manual holding. By adjusting the position of the collar 26 on the arbor, the compression of the spring 24 may be varied to increase or decrease the bearing pressure of the collar 16 on the washer 20. By proper adjustment the frictional resistance to turning may be set substantially to equal the turning moment of the last at the end of the last pin so that the arbor will not turn unless manual turning force is applied to the handle 54 or to the last.

While there has been considerable progress in standardizing the size of the last thimble hole, it is quite common to find lasts with thimbles smaller or larger than standard thimbles and frequently with thimbles so worn that the last pin described above does not have sufficient range to insure locking. A modified form of the invention designed to meet a greater range or variation in the size of the thimble holes is illustrated in Figs. 5, 6, 7 and 8. The only difference in this modified form lies in certain changes in the last jack P,

the method for supporting the same and the support being identical in every respect to that previously described. In this form the last jack comprises a sleeve 80 arranged to extend through the bore 38 in the enlarged end 36 of the arbor 10, the upper end of the sleeve having integral therewith a C-shaped head 82 the lower arm 84 of which bears against the enlargement. The lower end of the sleeve 80 extends below the enlargement and a substantially semicircular portion 86 of the sleeve is cut away flush with the lower surface of the enlargement. A semicircular plate 88 is seated in the cut-away portion of the sleeve and is screwed to the sleeve against the enlargement whereby the sleeve is held in the bore. A semicylindrical member 90 is formed integral with the plate 88, the member extending downward, as viewed in Fig. 5, and forming one half of a last pin. The plate 88 is also provided with a downwardly projecting flange 92 for preventing relative movement between the last pin and the last, as heretofore described in connection with the first form of the invention.

A spindle 96 is rotatably mounted in the sleeve 80 and an extension 94 formed at one end thereof forms the other half of the last pin the two halves of the last pin lying side by side with their inner faces in adjacent substantially parallel planes. A lever 98 is fixed to the spindle 96 by a pin 100, the lever serving to turn the spindle in the sleeve. The upper arm 102 of the C-shaped head is provided with an aperture 104 for the reception of the neck 106 of the handle 108 which is fixed to the arm by a set screw 110. A recess 122 is formed in the neck of the handle and serves as a bearing for the free end of the spindle 96. When the spindle is turned in the sleeve, the movable half 94 of the last pin will turn angularly with respect to the fixed half 90 of the last pin on an axis through one of its longitudinal edges, as shown in Fig. 7. Since the spindle 96 turns on its own axis to accomplish this turning of the movable half of the last pin about a longitudinal edge, the halves of the last pin are arranged to lie on opposite sides of one diameter of the spindle 96, as illustrated in Figs. 6 and 7, so that the longitudinal edge of the movable half of the last pin lies substantially along the axis of the spindle 96.

The spindle 96 is turned in one direction by a spring 114 disposed under torsional displacement about the free end thereof, one end of the spring being anchored to the handle 108 and the other end to the lever 98. The spring normally holds the spindle so that the parts of the last pin are opened out angularly with respect to each other, that is, in their locking position (Fig. 7). The movable half 94 of the last pin may be returned to a nonangular position to release the last by pressing a thumb-piece 116 integral with the lever 98 whereby the spindle is turned against the opposition of the spring. Due to the proximity of the two halves of the last pin, there is a tendency for them to bind as the movable half of the last pin is turned with respect to the fixed half. To eliminate this, a semisegmental strip has been removed along the longitudinal edge 118 of the movable half of the last pin, as shown in Figs. 6 and 7. To prevent damage to the last pin, for example, by forcing the movable half of the last pin in either direction, and to limit the degree of opening so that the operator will not have to move the thumb-piece through its full range when working with lasts having small thimbles, limit screws 120 and 122

are provided (Fig. 8). The screws are adjustably threaded through the back portion of the C-shaped head 82 and their ends are arranged to bear against the lever 98.

In using the device, as shown in Fig. 1, the thumb-piece 76 is pressed to align the parts 52 and 68 whereupon the last is placed upon the last pin and the thumb-piece is released, thereby locking the last on the last pin. A similar procedure is followed when using the device shown in Fig. 5; that is, the thumb-piece 116 is provided to close the parts 90 and 94 of the last pin, the last is placed upon the contracted pin, and the thumb-piece is then released, thereby locking the last on the last pin.

In the two forms of the invention just described the operator must manually operate the locking means during the mounting and dismounting of the last. In some classes of work it is desirable to have a last jack upon which a last may be placed and removed without manipulation, which naturally relieves the operator to a great extent and permits faster operation. To this end, the last jack illustrated in Figs. 1 to 4 may be mounted on a modified support whereby movement of the last jack from a loading position to an operating position automatically locks the last on the last pin, and the return of the last jack from operating position to loading position releases the last. When the last jack is so mounted the thumb-piece on the lever 68 may be omitted.

As illustrated in Figs. 9 to 11, the arbor 10 is mounted in the sleeve 12, as heretofore described, but the spring 24 is omitted, thereby permitting movement of the arbor longitudinally in the sleeve 12. In this form the turning moment produced by the last at the end of the last pin is offset by a counterweight to be described hereinafter and, therefore, the friction washer 20 and collar 16 are replaced by a washer 123 and bolt 125 which serve only to retain the arbor in the sleeve.

The last jack in Fig. 9 is shown in what will be hereinafter called its loading position, that is, in readiness for receiving the last. In this position the part 62 is maintained in a position concentric with the part 58 of the last pin 40 by a cam roll 126 (Fig. 10) arranged to co-operate with the lever 68, hereinafter in this form of the invention called the cam dog, to prevent the cam dog from being turned by the spring 74 and thereby to hold the spindle 64 in such a position that the part 62 is concentric with the part 58. The cam roll 126 is mounted on a stud 128 carried by one arm 130 of a fork-shaped member 132 secured to the free end of the sleeve 12 by means of screws 134. The arms 130 of the member 132 extend along opposite sides of the C-shaped head 42 and prevent rotation of the last jack in the enlargement 36, and also prevent angular rotation of the last jack about the horizontal axis of the arbor 10.

The last jack may be moved from the aforesaid loading position to a position to be hereinafter called the operating position. To move the last jack into operating position, the operator places the last upon the last pin in the loading position (Fig. 9) and then pulls on the jack or the handle 54 to move the arbor 10 to its extended position with respect to the sleeve 12. During this movement, the C-shaped head 42 clears the ends of the arms 130, and the cam dog 68 is removed from the restraining influence of the cam roll 126 so that the cam dog 68 is

turned by the spring 74, thereby causing the part 62 to grip the last thimble 60 (Fig. 2). In the operating position it is clear that by grasping the handle 54 the operator may move the last jack angularly about the horizontal axis of the arbor 10, and may also turn the last jack about its vertical axis in the enlargement 36 of the arbor 10.

For the reasons previously indicated it is desirable to counterbalance the weight of the last so that the last jack, with the last mounted on the last pin, will remain in whatever position it occupies when the operator releases his grasp on the handle. This is accomplished in the present instance (Fig. 11) by placing a counterweight 136 on the end of an arm 138 which is secured to a collar 140 surrounding the neck 52 of the handle 54. The counterweight 136 is movable longitudinally of the arm 138 and may be fixed at any position along its length by means of a set screw 142. The adjustment provided by this arrangement permits the operator to obtain a substantially perfect balance for any last mounted on the last jack in spite of the variation in weight of different lasts.

After the spraying or coating operation has been completed, the operator pushes the last jack back toward the loading position to release the last. Preparatory to this operation, however, the C-shaped head 42 must be turned to such a position that it will readily enter the space between the arms 130 of the member 132. In order to relocate the C-shaped head 42 in the proper position, a spring-pressed plunger 144 is provided in the enlargement 36 which co-operates with a recess 146 formed on the under surface of the C-shaped head so that the operator may turn the handle 54 until he feels the spring-pressed plunger snap into the recess 146. The last jack may then be moved back toward the sleeve 12 and the C-shaped head will be in proper position to move between the arms 130 without interference. As the last jack is pushed into position between the arms 130, the cam roll 126 will engage the cam dog 68 and turn it radially into the position shown in Fig. 10 to bring the part 62 into concentric relation with the part 58 of the last pin, whereupon the last shoe will fall from the last pin.

In operation, therefore, it is clear that the operator may with one hand place the last shoe upon the last pin, move it into operating position, turn it while in operating position so that access may be had to all parts of the shoe, return it to the loading position, and release it, while he holds the spray gun in the other hand.

Having described my invention, what I claim as new and desire to secure by Letters Patent of the United States is:

1. A device for holding a last comprising a support, a last pin mounted thereon upon which the last may be placed, and means for locking said last on the last pin, said last pin being rotatable about its own axis on the support, tiltable with the support about a horizontal axis, and movable in a horizontal plane with the support about a vertical axis whereby the last may be moved freely from one position to another.

2. A device for holding a last comprising a support, a last pin upon which the last may be placed, means for retaining the last on the last pin, an arbor for holding the last pin on the support, a collar on said arbor, and a spring mounted on said arbor between the collar and

the support, said collar being movable on the arbor to shorten the distance between the collar and the support.

3. A device for holding a last comprising a support, a last pin upon which the last may be placed, means for retaining the last on the last pin, an arbor for holding the last pin on the support, said support having a sleeve associated therewith for the reception of the arbor, a collar on said arbor, a spring mounted on said arbor between the collar and the adjacent end of the sleeve, a collar fixed to the end of the arbor opposite the other end of the sleeve, and a washer disposed between the second-named collar and the end of the sleeve, the first-named collar being movable on the arbor to compress the spring whereby the washer is squeezed between the second-named collar and the end of the sleeve.

4. A device for holding a last comprising a support, a last pin associated with said support, locking means on said last pin, said locking means comprising a rounded portion of substantially the same cross section transverse to its axis as the last pin aligned end to end therewith, said portion being movable about an offset axis substantially parallel to the axis of the last pin to cause its peripheral surface to be eccentric to the surface of the last pin and to bind against the inner side of the last pin hole, a head formed integral with the last pin, a handle fixed to said head whereby the last pin may be turned, and means mounted on said head and movable relative thereto to move the locking means from eccentric to concentric position.

5. A device for holding a last comprising a support, a last pin associated with said support, locking means forming a part of said last pin for retaining a last thereon, said locking means being movable into and out of locking position by rotation about an offset axis substantially parallel to the axis of the last pin, a head formed integral with the last pin, a handle fixed to said head whereby the last pin may be turned about horizontal and vertical axes, means mounted on said head for normally holding the locking means in operative position, and a handle for moving the locking means to inoperative position.

6. A device for holding a last comprising a support, a last pin associated with said support, locking means forming a part of said last pin for retaining a last thereon, a head formed integral with the last pin, a handle fixed to said head whereby the last pin may be turned, a lever mounted on said head, a spring anchored at one end to the handle and at the other end to the lever for urging the lever to turn in a direction to cause the locking means to lock the last on the last pin, and a handle on said lever whereby it may be manually turned to render the locking means inoperative.

7. A device for holding a last comprising a support, a last pin associated with said support, said last pin comprising two portions of substantially the same cross section, means for urging one portion to a laterally displaced position with respect to the other portion, and means for moving said first-named portion into alignment with the second-named portion, said last pin being rotatable on its own axis on said support, tiltable with the support about a horizontal axis, and movable in a horizontal plane with the support about a vertical axis.

8. A device for holding a last comprising a

support, a last pin associated with said support, said last pin having two portions of substantially the same diameter movable relatively to each other, one portion having a bore formed longitudinally thereof, a spindle disposed in said bore, the other portion being fixed to said spindle, and means for urging said spindle to turn in said bore to displace said second-named portion laterally of said first-named portion, said last pin being rotatable about vertical and horizontal axes and movable in a horizontal plane together with the support about a vertical axis.

9. A device for holding a last comprising a support, a last pin mounted thereon, said last pin comprising two parts, a handle associated with one part, said part having a longitudinal bore therein, a spindle disposed in said bore, said other part being fixed to said spindle, a spring mounted on said first-named part whereby the spindle is urged to turn in a direction to displace the second-named part laterally of the first-named part, and a handle fixed to said spindle whereby the same may be turned to a position in which the second-named part is concentric with the first-named part.

10. A device for holding a last comprising a support and an elongate last pin mounted on said support, said last pin comprising two members, one of which is rotatable, arranged to lie side by side with their inner faces in adjacent substantially parallel planes, means for urging one of said members to turn about its length to a position wherein its inner face lies at an angle to the inner face of the other of said members, and means for returning said first-named member to a nonangular position with respect to the second-named member.

11. A device for holding a last comprising a support, a last pin mounted on said support, said last pin comprising two semicylindrical members having adjacent flat faces, a spindle operably connected to one of said semicylindrical members, means for urging said spindle to turn to a position to cause its flat face to lie at an angle to the flat face of the other semicylindrical member, and means for turning said spindle so that the flat face of said first-named semicylindrical member contacts with the face of the second-named semicylindrical member.

12. A device for holding a last comprising a support, a last pin mounted on said support, said last pin comprising two portions, one portion being movable angularly about one of its longitudinal edges relatively to the other whereby the diameter of the last pin may be increased, means for constantly urging the movable portion to take up an angular position with respect to the other portion, and means for manually holding the movable portion in nonangular relation to the other portion.

13. A device for holding a last comprising a support and a last pin mounted on said support, said last pin being split diametrically, one half of said last pin being fixed and the other half being movable angularly with respect to the fixed half about an axis parallel to an edge of the fixed half.

14. A device for holding a last comprising a support and a last pin mounted on said support, said last pin being split diametrically, one half of said last pin being fixed and the other half being movable angularly about an axis parallel to an edge of the fixed half, said parallel axis lying within a radius of said fixed half.

15. A device for holding a last comprising a

support, a last pin mounted on said support, said last pin comprising two portions, one portion being movable angularly about a longitudinal edge with respect to the other whereby the diameter of the last pin may be varied, means constantly urging the movable portion to take up an angular position with respect to the other portion, means for manually holding the movable portion in nonangular relation to the other portion, and a pair of screws adjustable to limit the turning movement of the movable portion in either direction.

16. A device for holding a last comprising a support, a last pin mounted on said support, said last pin comprising two substantially semicylindrical halves, one half having a longitudinal semisegmental portion removed therefrom to provide a surface normal to its diametrical face, said half being arranged for pivotal movement about the edge formed by the intersection of said normal surface and said diametrical surface whereby the diameter of the last pin may be varied.

17. A device for holding a last comprising a support, a sleeve rotatably mounted on said support, a member fixed to one end of said sleeve, a spindle rotatably mounted in said sleeve, a second member associated with said spindle and movable therewith, said second member being constructed and arranged to form with said first member a cylindrical last pin, and means for moving the second-named member relatively to the first-named member to vary the diameter of the last pin.

18. A device for holding a last comprising a support, a last pin associated with said support upon which the last may be placed, and means for retaining said last on the last pin, said support and said last pin being movable as a unit in an arc about a vertical axis, said last pin being movable horizontally to and from the support, angularly about a horizontal axis and rotatably on its own axis, said movements being obtainable in any order of sequence so that the last may be moved freely from one position to another.

19. A device for holding a last comprising a support, a last pin associated with said support upon which the last may be placed, and means for retaining said last on the last pin, said support comprising a bracket, an arm mounted on said bracket for movement in a horizontal plane about a vertical axis, and an arbor telescopically slideable on said arm and rotatable about its horizontal axis, said arbor having an aperture at its end receiving said last pin for rotation about its own axis.

20. A device for holding a last comprising a support, a last pin associated with said support upon which the last may be placed, means for retaining said last on the last pin, an arbor movable horizontally from a loading position to an operating position on said support, said arbor having an aperture at its end receiving said last pin for rotation about its own axis, and means on said support to prevent rotation of the last pin in its loading position.

21. A device for holding a last comprising a support, a last pin associated with said support upon which the last may be placed, means for retaining said last on the last pin, an arbor movable horizontally on said support from a loading position to an operating position, said arbor being rotatable about its horizontal axis and being constructed and arranged to support the last pin,

and means fixed to said support to prevent rotation of the last pin about the horizontal axis of the arbor and about its own axis when the arbor is in loading position.

22. A device for holding a last comprising a support, a last pin upon which the last may be placed, an arbor arranged to hold said last pin on said support, said arbor being movable horizontally on said support from a loading to an operating position, means on said support for maintaining the last pin in a predetermined position for loading, said last pin in operating position being movable rotatably about its own axis, and means for relocating said last pin about its own axis so that when it is moved toward loading position it will occupy said predetermined position with respect to said first-named means.

23. A device for holding a last comprising a support, a last pin upon which the last may be placed, means for retaining the last on the last pin, an arbor for holding the last pin on the support, said arbor being movable about its horizontal axis, and means associated with said last pin to counterbalance the last so as to prevent it from turning about the horizontal axis of the arbor.

24. A device for holding a last comprising a support, a last pin upon which the last may be placed, means for retaining the last on the last pin, an arbor for holding the last pin on the support, said arbor being movable about its horizontal axis, and means associated with said last pin to counterbalance the last so as to prevent it from turning about the horizontal axis of the arbor comprising an arm fixed to said last pin, a counterweight slidably mounted on said arm, and means to fix the weight at any position along the length of the arm.

25. A device for holding a last comprising a support, a last pin mounted on said support upon which the last may be placed, said last pin being movable on said support from a loading to an operating position, means on said last pin for locking the last on the last pin, means urging said locking means into locking position, a cam dog connected to said locking means operative to move said locking means into inoperative position, and a cam roll on said support arranged to engage the cam dog when the last pin is in loading position and to hold the locking means inoperative.

26. A device for holding a last comprising a support, a last pin mounted on said support upon which the last may be placed, said last pin being movable on said support from a loading to an operating position, means on said last pin for locking the last on the last pin, means urging said locking means into locking position, a cam dog connected to said locking means operative to move said locking means into inoperative position, and a cam roll on said support arranged to engage the cam dog when the last pin is in loading position to restrain the means urging said locking means into locking position, said cam roll releasing said cam dog upon movement

of the last pin from loading to operating position. *Relative to machine cut given in last table* $\Delta = 27.4$ *unit for holding a last commencing*

27. A device for holding a last comprising a support, a last pin mounted on said support upon which the last may be placed, said last pin being movable on said support from a loading to an operating position, means on said last pin for locking the last on the last pin, means urging said locking means into locking position, a cam dog connected to said locking means operative to move said locking means into an operative position, and a cam roll on said support arranged to engage the cam dog when the last pin is in loading position to hold the locking means inoperative, said cam roll co-operating with said cam dog to return the locking means from locking position to an inoperative position when said last pin is moved from operating position to loading

position. By Dr. E. G. Bissell, 1919. See No. 10,740,000.
0. **28.** A device for holding a last comprising a support, a last pin associated with said support, said support having an aperture therein adapted to receive the last pin, and a head formed integral with one end of said last pin adapted to rest against one side of said support, said pin being held in the aperture of the support by a collar fixed to the last pin against the other side of the support. (See also 1919, 10,740,000.)
1. **29.** A device for holding a last comprising a

support; a last pin associated with said support, a head formed integral with said last pin, a handle fixed to said head whereby said last pin may be manually rotated, a spring pressed latch mounted on said support, and a recess in said head, said latch being adapted to engage said recess to hold said head in a predetermined position with respect to the support.

30. A device for holding a last comprising a support, a last pin associated with said support, locking means on said last pin for retaining a last thereon, said locking means being moved into and out of operative position by rotation about an offset axis substantially parallel to the axis of the last pin, a head formed integral with the last pin, a handle fixed to said head whereby the last pin may be turned, a cam dog mounted on said head co-operating with said support to hold the locking means inoperative, and a spring mounted on said head for urging said locking means into locking position. *REINHOLD A. SI*

50 means into locking position.

31. A device for holding a last comprising a support, a last pin associated with said support, locking means forming a part of said last pin for retaining a last thereon, a head formed integral with the last pin, a handle fixed to said head whereby the last pin may be turned, a cam dog mounted on said head having a hub thereon the end of which is journaled in the handle, said cam dog co-operating with said support to hold the locking means inoperative, and a spring disposed on said hub, one end of the spring being fixed to the cam dog and the other end to the handle whereby the cam dog is urged to turn in a direction to cause said locking means to lock the last on the last pin.
